UNITED STATES PATENT OFFICE.

WILLIAM A. SMITH, OF DETROIT, MICHIGAN, ASSIGNOR TO CHICAGO PNEUMATIC TOOL COMPANY, OF NEW YORK, N. Y., A CORPORATION OF NEW JERSEY.

OILER FOR PNEUMATIC TOOLS.

Application filed September 5, 1922. Serial No. 583,292.

To all whom it may concern:

Be it known that I, WILLIAM A. SMITH, a citizen of the United States of America, residing at Detroit, in the county of Wayne 5 and State of Michigan, have invented certain new and useful Improvements in Oilers for Pneumatic Tools, of which the following is a specification, reference being had thereto in the accompanying drawings.

10 This invention relates to oilers of the type which is applicable for lubricating the working parts of fluid operated mechanisms wherein it is necessary to overcome the fluid pressure in order to introduce the lubricant. 15 In oilers of this type it is necessary to provide some means to prevent the escape of fluid pressure while the lubricant is being introduced.

During the operation of pneumatic tools 20 it is important that the working parts be lubricated frequently but the operators often neglect this duty because it interferes with their production output. It is therefore important to provide an oiler which is simple 25 to manipulate and which can be conveniently carried.

In my improved construction I have provided a compact device which is adapted to be carried by the operator in his pocket and 30 which can be manipulated very simply while the tool is in operation. In general construction there is a casing containing an oil reservoir on which is mounted a plunger pump connected to an ejecting nozzle which 35 is provided with a conical tip adapted to seat in a fitting upon the tool to be lubricated. The effective area of the plunger pump is made considerably greater than the area of the nozzle tip so that the pressure applied to 40 the plunger for forcing the lubricant into the fitting is greater than the back pressure exerted by the operating fluid upon the nozzle whereby an effective seal is maintained between the nozzle and the fitting.

45 In the drawings:

Fig. 1 is an elevation of the improved oiler;

Fig. 2 is a cross section of the same with the plunger in rearward position;

50 Fig. 3, is a similar section with the plunger forward showing the nozzle engaging the tool to be lubricated;

Fig. 4 is an end elevation.

In my preferred construction A represents 55 a substantially rectangular container hav-

ing at its upper end the cylinder B containing the piston C which may be reciprocated by the stem D and the handle D'. The cylinder is closed at its rear end by the cylinder head B' which is apertured at B² to allow 60 the stem D to pass therethrough. A spring E is sleeved upon the stem D between the piston and the cylinder head to assist in the operation of the plunger. The cylinder communicates through a passage F with the 65 lower portion of the chamber A' of the container and also communicates at its forward end with the nozzle tube G which is secured to the casing at G'. The outer end of the nozzle has a tapering conical surface H and 70 the nozzle is also provided with a longitudinal bore G² for the passage of the lubricant. Between the nozzle and the cylinder is a check valve I consisting preferably of the ball I' which is normally held in engagement with the conical seat I² by means of a spring I³ which abuts against the inner end 75 G³ of the nozzle tube. J is a detachable plug or cap preferably located in the base of the casing for filling the chamber with lubricant.

M represents a portion of a tool to be lubricated such as a pneumatically operated drill which is provided with a fitting K in threaded engagement therewith. The fitting is recessed to form a conical seat K' which is adapted to fit the conical surface H of the nozzle and form a seal therewith when pressure is applied upon the plunger pump. The fitting is also provided with an axial bore N, which extends therethrough and forms a conical seat N' for the check valve L which is normally held in engagement with the seat by the spring L'.

The cross sectional area of the piston is 80 made considerably larger than the opening K' in the fitting so that in the operation of the device it is only necessary to place the nozzle in the fitting and reciprocate the plunger by means of the handle D'. Sufficient pressure must be exerted upon the handle to build up a pressure in the cylinder equal to the fluid pressure in the tube, but because of the relatively large area of the piston the pressure of the nozzle upon the fitting will be greatly in excess of the back pressure in the tube thereby forming an effective seal and preventing any leakage at 85 this point.

Thus it will be seen that I have provided

a very simple construction which may be conveniently carried by the operator and which may be used for the lubrication of a pneumatic tool by simply placing the nozzle in a fitting upon the tool and operating the pump handle.

What I claim as my invention is:

An oiler for pneumatic tools comprising a lubricant container adapted to be carried in the operator's pocket, a nozzle secured thereto having its outer end adapted to seat in a fitting, a cylinder, a manually operable plunger in said cylinder, a check valve between said cylinder and nozzle, a valveless inlet port in said cylinder overrun by said

piston and communicating with said container, resilient means for normally holding said plunger in a position to seal said inlet port, and a handle for reciprocating said plunger to eject the lubricant, the nozzle forming a seal with the fitting by the pressure exerted upon said plunger during its ejecting stroke, the cross-sectional areas of the piston and the nozzle being so proportioned as to provide for the ejection of the lubricant through the nozzle with sufficient force to overcome the fluid or line pressure of the tool. 20 25

In testimony whereof I affix my signature.

WILLIAM A. SMITH.
